US0D1014763S

(12) **United States Design Patent** (10) Patent No.: **US D1,014,763 S**
(45) Date of Patent: ** Feb. 13, 2024

(54) **FLEXIBLE APPLICATOR**

- (71) Applicant: **CYNOSURE, LLC**, Westford, MA (US)
- (72) Inventors: **Jeffrey Michael Treen**, Nashua, NH (US); **Daniel B. Masse**, Windham, NH (US); **James Boll**, Auburndale, MA (US); **Jeffrey Simon**, Everett, MA (US); **David Sonnenschein**, Dorchester Center, MA (US); **Samuel Bruce**, Malden, MA (US)
- (73) Assignee: **CYNOSURE, LLC**, Westford, MA (US)
- (**) Term: **15 Years**
- (21) Appl. No.: **29/857,256**
- (22) Filed: **Oct. 20, 2022**

CLAIM

The ornamental design of a flexible applicator, as shown and described.

DESCRIPTION

FIG. 1 is a perspective view of a flexible applicator;
FIG. 2 is a view of one side of a flexible applicator;
FIG. 3 is a view of another side of a flexible applicator;
FIG. 4 is a rear view of the flexible applicator;
FIG. 5 is a front view of the flexible applicator;
FIG. 6 is a top view of the flexible applicator; and,
FIG. 7 is a bottom view of the flexible applicator.
Broken lines, the area within them, and the area bounded by both broken lines and solid lines depict environmental subject matter and form no part of the claimed invention.
